UNITED STATES PATENT OFFICE

HORACE KINTON WARNER AND GEORGE ROBERT ELLIOTT, OF AUCKLAND, NEW ZEALAND, ASSIGNEES TO WARNEIL PATENTS LIMITED, OF AUCKLAND, NEW ZEALAND, A COMPANY OF NEW ZEALAND

ELECTRIC IRON

Application filed March 17, 1931, Serial No. 523,328, and in New Zealand July 24, 1930.

This invention has been devised with the object of providing improved safety switch devices for combination in an ordinary type of electric iron for the purpose of controlling the current supply to cause it to be automatically turned on when the iron handle is grasped by the hand, as in the use of the iron, and to be turned off when such grasp is loosened. Also these means are of such a nature as to provide for the iron being rested on its heel and by so doing, at the will of an operator, to either leave the current off, or to turn it on, as may be desired.

The invention comprises the combination within the iron handle, of switch mechanism that is interposed within the current supply lead to the iron, and is so made that in normal conditions the switch is open to stop the current flow, but is closed when the handle is grasped in the user's hand and thus to provide for the supply to the iron heating element. This switch mechanism has embodied therewith means whereby the switch may be closed when the iron is resting on its heel, in order thus to provide for the heating of the iron preliminary to its use.

In fully describing the invention reference will be made to the accompanying drawing, in which:—

Figure 1 is a side elevation of the complete iron.

Figure 2 is a longitudinal side sectional elevation of the iron handle and the switch mechanism arranged therein.

Figure 3 is a cross sectional elevation on the line 3—3 of Figure 2.

Figure 4 is a plan showing the iron handle in section and the switch mechanism in plan.

In giving effect to the invention the handle 10 is made hollow, as by being made in upper and lower halves secured together by means of screws 11. The space enclosed by the upper and lower halves is continued rearwardly out through the handle end in the form of a central bore 12 and two side wire grooves 13 formed in the upper surface of the lower half and which are closed in when the upper half is secured over them.

The lower half of the handle is also formed

with a slot 14 extending longitudinally therein and opening down through to the bottom.

A horizontal base board 15 of suitable insulator material is affixed to the upper surface of the lower half of the handle so that it extends within the hollow space thereof, and this plate at its rear end is fitted with two terminal screws 16, one near each side and in the lines of the respective grooves 13. Near its forward end, the plate is fitted with two contact studs 17, one near each side, which are electrically connected respectively with the terminal screws 16 on the corresponding edges of the base board, as for instance by means of the metallic strips 18 let into the surface of such board.

The connecting flex for the iron is led to it in the usual manner by attachment to the two point plug 19 but the supply lead of the flex, instead of being connected directly to its terminal in such plug, is carried first in through one of the grooves 13 and is attached to one of the terminal screws 16, and the plug terminal is then connected to the other terminal screw 16. Thus the supply circuit is broken, but it may be closed by the electric bridging of the two studs 17. The mechanism devised provides for this being done under the circumstances before-mentioned.

This mechanism comprises a switch plate or disc 20 that is arranged upon the base board 15 by being mounted on a centrally disposed pivot 21, and is so made that in one position of its turning movement it bridges the studs 17, while in another it frees them from connection. A stem piece 22 is mounted in suitable guides 23 to extend longitudinally along above the base board and above the switch plate 20. This is connected to the switch plate by means of a spring connection 24 attached to the plate at a distance from its centre and so arranged and made that upon an inward movement of the stem, a pull is exerted on the spring to turn the switch plate on its pivot in the direction to bridge the studs 17, and on the reverse movement, to turn it reversely to break such connection. The turning of the switch plate is

made sufficiently resistant to provide that the spring requires tensioning before the plate will turn in order thus that quick make and break of the switch is effected in the 5 working of the apparatus.

The stem 22 is kept normally forced outwardly to turn the switch plate to the "off" position, by means of a spring 25 surrounding it and arranged in compression between 10 the guide 23 and a shoulder upon the stem end. When therefore the stem is free, the switch is open to cut off the power supply.

A bell crank lever is pivoted in the rear end of the base board 15, such lever having 15 one arm 26 extending upwardly and fitting loosely within a slot 27 formed in the rear end of the stem 22, and its other arm 28 extending downwardly into the slot 14 of the iron handle. A bow shaped lever 29 20 is arranged to extend along within this slot and has its front end pivoted to the forward end of the base board 15 while its rear end is articulated to the arm 28 of the bell crank lever. This bow lever has its bow extending 25 downwardly, and it is designed on upward movement being given to it, to turn the bell crank lever and to force the stem 22 in a forward direction to close the switch. The amount of this downward curve is such as to 30 cause the lever to project beyond the surface of the handle bottom in order thus that when the handle is grasped by the hand closing upon it, the lever is turned upward to close the switch and retain it closed so long 35 as the grasp is retained. On the grasp being released, the switch will automatically open under the action of the spring 25. Thus the desired effect of keeping the current supply on while the iron is being used, 40 and automatically turning it off when the use ceases, is obtained.

To provide for the switch being closed when the iron is turned up on its heel, a presser bar 30 is provided and mounted to 45 slide in the handle bore 12 so that one end engages the rear of the stem 22 while its other end projects a distance beyond the rear of the handle. When the iron is turned up to rest on its heel, this bar will engage 50 the surface on which the iron rests, and when weight sufficient to overcome the spring 25 is exerted, will force the stem 22 inward to close the switch. The weight of 55 the iron itself, however, is not sufficient to overcome this spring 25 but will when added to by pressure, do so, and then will retain the stem in the inward position. Consequently the iron may be rested on its heel with the current supply broken, or closed, 60 according to the user's desire.

We claim:—

1. In electric irons, a hollow handle, a horizontal base board of insulator material arranged within such hollow, a pair of contact studs fixed upon the surface of such 65

base board and interposed in the current supply lead to the iron heating element, a bridging plate or disc mounted to rotate on such board and adapted in one position to connect the studs and in other to disconnect them, a stem piece mounted to slide longitudinally in the handle above the base board, connected to such bridging plate or disc by a tension spring, adapted when moved forwardly to turn it to the connecting 70 position, a spring acting on the stem piece and forcing it to the rearward, or disconnecting, position, a bell crank lever mounted to extend vertically in the handle and having an upwardly extending arm engaging 75 the rear end of the stem piece and its second arm extending rearwardly and downwardly, and a bow shaped lever arranged to extend along beneath the handle with its bow downward, and having its forward end pivoted 80 in the handle and its rear end articulated to the second arm of the said bell crank lever.

2. In electric irons according to claim 1, a presser bar fitted to slide within the rear end of the handle, having its forward end arranged to engage the rear end of the said stem piece and its rear end to project beyond the handle end.

In testimony whereof, we affix our signatures.

HORACE KINTON WARNER.
GEORGE ROBERT ELLIOTT.
